EXAMINER'S ROOM.

UNITED STATES PATENT OFFICE.

CHARLES PETIGNY-MEURISSE, OF NEW YORK, N. Y.

DESIGN FOR AN ORNAMENT FOR LADIES' WEAR.

SPECIFICATION forming part of Design No. 12,278, dated May 24, 1881.
Application filed March 8, 1881. Term of patent 3½ years.

To all whom it may concern:

Be it known that I, CHARLES PETIGNY-MEURISSE, of the city, county, and State of New York, have invented a new Design for Ornament for Ladies' Wear, of which the following is a full, clear, and exact description:

In the accompanying drawings, Figure 1 is a plan view of the upper side of my newly-designed ornament for ladies' wear. Fig. 2 is a plan view of the under side of the same.

An imitation of a bird's talon is made of any suitable material, and is covered with material to represent the color and the scales of a bird's talons. Such material are feathers and any kind of metal or glass beads, gold thread, pressed straw-braid, silk, &c. The claws D must be made of metal, to imitate the glossy appearance and the color (such as yellow, light and dark gray, bluish tints, &c.) of the claws.

Two bands, A, are passed around this imita-

tion talon—one near the middle and one at the rear end—which bands are united by a chain, B.

I am aware that real talons of birds have been mounted as pins for holding garments, sashes, ribbons, &c.; but this I do not claim.

Having thus described my invention, what I claim as new, and desire to secure by Letters Patent, is—

1. The design for an ornament for ladies' wear herein shown and described, consisting of an imitation talon of a bird encircled by two bands.

2. The design for an ornament for ladies' wear herein shown and described, consisting of an imitation talon of a bird encircled by two bands united by a chain.

CHARLES PETIGNY-MEURISSE.
